SPOT MILLING TUBULAR BLANK FOR
PROPELLER BLADESDwillard J. Davis, Detroit, Mich., assignor to
Avco Manufacturing Corporation, a corpora-
tion of Delaware

Application March 8, 1945, Serial No. 581,657

19 Claims. (Cl. 90—14)

1

The invention relates to machines for use in providing hollow steel propeller blades with the desired predetermined wall-thickness, which varies in different portions of the blade according to the stresses to which they are subjected in use.

Heretofore, in fabricating hollow steel propellers, the wall-thickness of partially fabricated tubular blanks which are to be used in the working portions of the blades, was measured at different spots or stations. The spots were then marked to indicate any excess of wall-thickness. The outer periphery of the blank was then abraded, usually by a belt sander, to remove the excess metal. This abrading was done by approximation or guess from observation and frequently resulted in abrading too much metal from the blank and leaving insufficient wall-thickness, which rendered the tubular blanks unusable or lacking in the requisite thickness for safe use, which necessitated scrapping such blanks. In propeller blades great accuracy in wall-thickness is a desideratum.

One important object of the invention is to provide a machine for use in fabricating propeller blades with great precision in wall-thickness and uniformity in production. This object is attained primarily by milling or machining with great accuracy, spots of the tubular blank, so as to leave the desired thicknesses at different points on the outer surface of the blank, and then abrading the outer surface of the blank until the spots or depressions are blended into the surface of the blank and eliminated. This makes it possible to accurately determine when the abrading process should be discontinued to leave the correct wall-thickness of the metal at the different points and avoids the production of blades which must be scrapped on account of thin walls.

Another object of the invention is to provide a machine for expeditiously milling spots in the wall of the blank for the aforesaid purpose.

Another object of the invention is to provide a machine for milling or machining spots of different controlled depths according to the desired variations in wall-thickness in different portions of the blade.

Another object of the invention is to provide a machine for the aforesaid purpose which is readily adjustable to mill spots in the blank on axes at right angles to longitudinally curved or tapered tubular portions and straight cylindrical portions of the blank.

Another object is to provide a machine which can be expeditiously operated for production and loaded with a blank for milling spots in circumferential and longitudinal series in different portions of the blank.

Another object of the invention is to provide a machine for this purpose in which the blank is

2

rotatable for milling spots in circumferential series and which includes means for locking the blank against rotation during milling operations.

Another object of the invention is to provide a machine which includes means for indicating to the operator when the contact for engaging the inner periphery of the blank is engaged for cooperating with a stop-member for the tool for controlling the depth of the cut so that the operator will not operate the tool to make the cut if there is interference between the inner member and the blank.

Other objects of the invention will appear from the detailed description.

15 The invention consists in the several novel features hereinafter described and more particularly defined by claims at the conclusion hereof.

In the drawings:

Fig. 30 is a detail section illustrating the contact-ball carried by one of the tilting beams for engaging the inner periphery of the tubular blank.

Fig. 31 is a detail section illustrating the milling tool in its relation to the inner contact for the blank, with a cut of a predetermined depth.

Fig. 32 is a side elevation of the brake mechanism for the vertical movement of the tool head.

Fig. 33 is a plan view of the parts shown in Fig. 32.

Fig. 34 is a plan view of the tilting beams, the outer of which carries the contact device for locking said beams before the spots are milled in the tubular blank.

Fig. 35 is a vertical section taken on line 35—35 of Fig. 34.

Fig. 36 is a horizontal section taken on line 36—36 of Fig. 35.

Fig. 37 is a vertical section taken on line 37—37 of Fig. 34.

Fig. 38 is a diagram of the electric circuits and hydraulic mechanisms, for controlling the brake for the vertical movement of the tool, the brake for the blank, the lock for the tilting beams, and the signals.

Fig. 39 is an end elevation of a modified form of mechanism for angularly shifting the tool.

Fig. 40 is a side elevation of the variable stop-device shown in Fig. 39.

Fig. 41 is a section taken on line 41—41 of Fig. 40.

The machine exemplifying the invention comprises generally: a bed for supporting the several mechanisms in accurately co-acting relation; a carriage for the tubular blank, which is longi-

tudinally movable and on which the blank is rotatable, for presenting different longitudinal points or stations on the blank to the spot milling tool; a roll which is calibrated to indicate the spots where the blank is to be milled; gearing for conjointly rotating the blank and the calibrated roll and maintaining them in co-related positions; brake means for locking the blank against rotation during the milling operations; a power driven tool for milling spots in the blank, which is vertically movable; mechanism for controlling the depth of the cuts made by the tool, which includes, a pivoted beam adapted to extend into the blank and is provided with a contact for engaging its inner periphery, a second beam outside of the blank and movable with the inner beam, a stop-member on the outer beam, and adjustable stop means movable vertically with the tool; means for locking the beams against vertical movement during the milling operations; means for adjusting the tool angularly to produce cuts in the blank substantially normal to longitudinally tapered or curved surfaces on the blank; brake means for arresting the lowering movements of the tool until the inner beam is engaged with the inner periphery of the blank; and means for signaling to the operator that the inner beam has engaged the blank periphery preparatory to a milling operation and also the completion of the milling cut.

The several mechanisms of the machine are supported on a solid bed 50 which is mounted on a rigid frame 51. Screws 52 carried by frame 51 are adapted to support the bed in a true horizontal plane so it will be retained level (Figs. 1 and 2). This is formed of sections, the ends of which are secured together by bolts 54 with a locking bar 55 fitting into and clamped in grooves in the contiguous end faces of the sections.

The carriage generally designated 57, for the tubular blank is movable longitudinally over the bed and comprises a left-hand end-frame, generally designated 58 (Figs. 15 and 16), for carrying the end *a'* of the tubular blade-blank *a*, a right hand end-frame generally designated 59 (Fig. 17), rods 60, 61 which secure said frames together for longitudinal movement over the bed. End-frame 58 is equipped with rollers 62 and frame 59 is equipped with rollers 63 which are adapted to travel on tracks 64 on the top-face of the bed 50. Each frame 58, 59 has secured thereto a bar 65 which slides in a longitudinal groove 66 in the bed 50 to insure precise rectilinear movement of the carriage over the bed and in a plane parallel to the longitudinal axis of the tubular blank. Rod 60 is provided with notches 67 corresponding to the predetermined longitudinal stations of the blank which are to be spot-milled.

The blade-blank *a*, before the spot-milling operations therein, is usually upset or swaged to form a shank-forming end *a'*, a straight cylindrical portion of *a*² to be formed into the face sections of the blade and a longitudinally tapered portion *a*³ between the portions *a'* and *a*². As well understood in the art, the wall-thickness usually tapers longitudinally from the shank to the tip of the blade. The portions used in the faces, leading and trailing edges of the blade are usually cam-turned to provide maximum wall-thickness, along said edges as at *a*⁴ and reduced thickness in the face portions between said edges (Fig. 27^b).

The shank-end *a'* of the blade is secured on the

carriage 57 for longitudinal movement over the bed 50 by a chuck or internal gripping device which comprises: a series of gripping shoes 70 (Figs. 22 and 25) which are adapted to grip the internal periphery of the blank-portion a' and are slideable in radial slots in a chuck-head 71, which is journaled in a supporting bracket 12 on end-frame 58; an expander 73 for shoes 70 which is axially slideable in head 71; and a hand-wheel 74 which is screw-threaded to the stem of expander 73, and adapted to axially shift the expander to secure the shoes 70 against the inner periphery of shank a' ; and an annular spring 75 for contracting the shoes 73 when they are released by the expander. A pair of rollers 76 on end-frame 58 and a pair of rollers 77 on end-frame 59 are adapted to support the tubular blank with its longitudinal axis co-axially aligned with the gripping chuck. This chuck is rotatable on carriage 57 so that the blank is rotatable for milling circumferentially spaced spots and is locked in its rotatively set position during the milling operations by brake-means which comprises (Figs. 15, 21) an air cylinder 80 which is supported on bracket 72, a piston in said cylinder 80 and provided with a stem 81, and a brake-shoe 82 adapted to be forced against the outer periphery of the blade-shank a' . Pipes 84 and 84^a are provided to alternately deliver air into and exhaust it from cylinder 80, as hereinafter described.

A roll 85 (Figs. 15 and 28) is calibrated as at 86 according to the longitudinal and circumferential locations of the spots to be milled, is rotatably mounted for synchronous rotation with the blank, and supported on the carriage 57 to move longitudinally therewith. One end of roll 85 is secured by a screw 88 (Fig. 23) to a trunnion 89 which is journaled in an anti-friction bearing 90 which is carried by a bracket 91 which is secured to end-frame 58. The opposite end of roll 85 (Fig. 24) is fixed to a trunnion 96 which is journaled in an anti-friction bearing in a bracket 96^a fixed to end frame 59. A gear 92 is keyed to trunnion 89, meshes with a gear 93 which is fixed to the chuck-head 71, for rotatively adjusting the blank a and roll 85 in unison, on the carriage 57. A clamp comprising members 95 pivoted to head 58 and a screw 97 (Fig. 16), is adapted to lock roll 85 against rotation while the blank is being positioned rotatively and secured on the chuck.

A plate 102 (Figs. 27 and 28) with a sight opening 103 for viewing the calibrations on roll 85 corresponding to the spot to be milled on the blank by a milling tool 105, is pivoted to the upper end of a bracket 104 which has its lower end fixed to the bed 50. The roll 85 in its longitudinal movement with the blade carriage 57 and its rotative movements on said carriage moves the calibrations 86 relatively to the sight-opening 103 to indicate the longitudinal and circumferential locations of the spots on the blank where the milling tool will operate on the blank and to indicate required wall thickness of the blank. A dog 104' is pivotally connected to the lower portion of bracket 104 and is provided with a tooth 104^a which is adapted to drop into the notches 67 in rod 69 for spotting and locking the carriage 57 and roll 85 against longitudinal movement, at different predetermined longitudinal stations.

The shanks of the blade blank are provided with punch marks 100 (Fig. 27^a) at each of its ends when the blank is cam-turned to define a longitudinal line for rotatively positioning the blank on the chuck corelatively with the calibrations on the roll 85. A pointer 101 is pivotally

supported on bracket 12 to register with punch mark 100 on the shank when the roller 85 is set to indicate the calibrations for the corresponding longitudinal line. In this manner the blank can be initially set on its chuck with the points on the blank to be spot milled correctly co-related to the calibration indicated at sight-opening for roll 85.

The machine comprises a suitable milling tool 105 (Figs. 9, 18 and 31) for cutting spots into the outer surface of the blank and power mechanism for driving the tool (Figs. 7, 10 and 18). The tool is mounted for vertical movement to and from the blank and is removably secured in a vertical driven spindle 110. The mechanism for driving the tool comprises an electric motor 128, a pulley 130 on the motor shaft, an endless belt 129, and a pulley 131 driven by belt 129 and secured to the upper end of the spindle 110, which is rotatably mounted in a sleeve 112. Motor 128 is supported on a frame or head 114 and sleeve 112 is slideable vertically in said head or frame. The sleeve 112 which carries tool 105 is vertically shiftable by a hand wheel 124 fixed to a shaft 125 which is journaled in head 114 and is provided with a pinion 125' which engages a rack 112' on sleeve 112. Springs 127 are applied to lift sleeve 112 and the tool 105 carried thereby. Head 114 which supports the tool and the power driven mechanism is clamped to a post 115. Post 115 is supported in a bracket 116 which is pivotally supported on a bracket 119 by a pin 118 to permit the head 114 to be tilted longitudinally of the blank for varying the angular relation of the axis of the tool to the outer surface of the blank. Bracket 119 is mounted on a bracket 120 which is fixedly secured on the bed 50.

The machine comprises mechanism for controlling the depth of the spot cuts of the tool 105 to leave the predetermined wall-thickness desired in the different portions of the blank. This mechanism comprises a beam adapted to enter the blank and which carries a contact or feel for engaging the inner periphery of the blank at the spot to be milled, a beam outside of the blank which carries a stop member controlled by the contact on said inner beam, and co-acting stop-means movable vertically with the tool and which is adjustable to vary the depth of the cut.

The beam, which enters the blank a is generally designated 140 (Fig. 1), comprises: an attaching-member 141, (Fig. 19), which secures said beam at one end to a cross-shaft 142, which is journaled in anti-friction bearings 143 which are supported on a bracket 144, a structural member 145, adapted to extend into the tubular blank, extending from and bolted to attaching-member 141, and stiffened by a truss-rod 146; a socket plate 147 secured to the distal end of member 145 by bolts and which is electrically insulated from said member, by an insulation plate 148 and sleeves 149 (Fig. 30); and a contact ball 150 confined in the socket in plate 147 and adapted to engage the inner periphery of the blank in axial alignment with the milling tool 105. A mating beam 155 is adapted to extend along the outside of the blank a and is fixed to an attaching-member 156 which is fixed to cross-shaft 142, and has a block 158 (Fig. 7) fixedly secured to the distal end. A stop-member 159 is secured on the top of said block. The stop-member 159, through beams 140, 155, moves vertically with the contact-ball 150 on beam 140, so that member 159 will be positioned correspondingly to ball 150 as it is moved into

engagement with the inner periphery of the blank *a*. Stop-member 159 is secured to block 158 (Fig. 37) by screws 161, and electrically insulated from said block by sleeves 162 and a strip 163. Counterweights 151 are carried by a rod 152 which is fixed to a plate 152' which is fixed to attaching-members 141, 156 for pressing the contact-ball 150 into engagement with the inner periphery of the blank *a*.

The means for co-acting with the stop-member 159 on beam 155 which is controlled by the inner periphery of the blank *a*, to limit the depth of the cut of tool 105, is mounted on a housing or head 111 which is clamped to sleeve 112 and is movable vertically with said tool and adjustable to selectively control the depth of the cuts according to the wall-thickness desired in different portions of the blank. This means comprises: a stem 185 (Figs. 8, 18) adapted to engage the stop-member 159 on beams 155 and secured to a plunger 186 which is slidably mounted in the housing 111 and is provided at its upper end with an inclined cam-surface 190; a wedge-member 191 mounted in housing 111 to slide transversely of the plunger 186; a slideable yoke 192 (Fig. 29) secured to wedge-member 191; an index arm 193 fixedly secured by screws to a hub 200 on the front end of yoke 192; a stem 195 provided with a screw-thread 194 and keyed in forwardly projecting boss on housing 111; an index wheel 196 having a hub provided with a screw-thread engaging the screw-thread 194 on non-rotatable stem 195, with calibrations 197 which indicate the fractional rotations of the wheel 196 from a predetermined position on a pointer 198 on index arm 193; and a split collar 199 secured to an inner face of the hub of wheel 196 by screws and having a rib fitting in an annular groove in hub 200 of yoke 192 for imparting sliding movement to the yoke 192 and wedge-bar 191 by the axial movement of yoke 192 resulting from rotation of said wheel on the screw-thread 194 on stem 195. The front end of stem 195 is provided with annular grooves 202, which with the front bevelled edge of a sleeve 204 on wheel 196 indicate the rotations of the hand-wheel 196. The calibrations 197 on the said wheel 196 and grooves 202 indicate the position of the stem 185 for arresting the lowering movements of housing 111 and the tool 105 until said stem engages the stop-member 159 on beam 155. Rotative adjustment of hand-wheel 196, through its screw-threaded connection with stem 195 slides the yoke 192 to shift wedge-bar 191 laterally for shifting plunger 186 and stem 185 vertically, relatively to the housing 111 which is slideable with the tool 105 for arresting the tool 105 when it has milled spots to the correct depth to leave the desired wall-thickness in the blank at the respective spots. A spring 205, engaging a shoulder on plunger 186, holds the latter in engagement with cam-bar 191. This mechanism is adapted for micrometric adjustment and indications of the depth of the cut made by the tool 105, for the precision desired in the wall-thickness of propeller blades. During each downward milling stroke of the tool 105 by hand-wheel 124, the stop-plunger 185 will engage the stop-member 159 on beam 155, the position of which is controlled by the engagement of stop-member 150 on beam 140 with the inner periphery of the blank. For guiding the housing 111 and tool 105 rectilinearly and preventing deflection, a guide block 135 is fixed to

housing 111, and is slideable in a guide 136, which is fixed to the bracket 116.

A fluid controlled locking-mechanism (Figs. 7, 35 and 36) is provided for locking the beam 155 and stop-member 159 against movement during the milling operations of tool 105. This mechanism comprises a post 164, the upper end of which is fixedly secured in and depends from block 158; shoes 165, 167 for gripping post 164; springs 168 for releasing the shoes; a block 170 in which the shoes 167 are slidably confined and which is secured by bolts 171, to a bracket 172, which is secured to bracket 120; a wedge-bar 174 which is horizontally slideable between shoe 167 and the innerside 166 of bracket 172; a cylinder 176, supported by an extension on bracket 172, and connected to pipes 178, 179 for alternately delivering and discharging fluid under pressure; and a piston operable by said fluid and provided with a stem 180, which is coupled by a pin 181 to the wedge-bar 174.

In spot milling partially fabricated blanks for propeller blades, it is necessary for precision in leaving the necessary wall-thickness to operate the tool on an axis which is substantially perpendicular to the surfaces of the blank, and for this purpose it is necessary to vary the axis of the tool relatively to the blank where the latter has tapered or longitudinally curved portions. The pivot pin 118 is supported in the stationary bracket 119 and the bracket 116 which supports the post 115, the head 114 and the driving mechanism for the tool 105 is journaled on the pin 118, so as to permit the operation of the tool in different angular relations in a plane parallel to the longitudinal axis of the blank, so the axis of the tool will be perpendicular to the longitudinally curved or inclined surfaces on the blank, as diagrammatically indicated in Fig. 3. The bracket 116 is locked in its adjusted angular positions, (Figs. 9, 14 and 15), by a screw-clamp 209 threaded into an arm 210 which is fixed to the post 115 which is fixed in bracket 116; and extends through an arcuate slot 211 in a member 212 which is fixedly supported at the upper end of a bracket 213 (Fig. 12) which is secured to the bed 50. The member 212 has minute calibrations 214 for indicating the settings of the bracket 116 and the parts carried thereby.

Mechanism for shifting the bracket 116 comprises (Figs. 10, 12 and 13) an arm 215 depending from and fixed to bracket 116, a screw-shaft 216 journaled on the bed 50, a runner 217 on shaft 216 pivotally connected by pins 218 to arm 215, a transverse shaft 219 provided at the front of the bed 50 with a hand-wheel 220, and bevel-gears 221 between shafts 216 and 219.

Brake means is provided for the lowering movements of the tool 105 and comprises (Figs. 11, 32 and 33) a finely-toothed ratchet-wheel 224 which is fixed to the shaft of hand-wheel 124; a toothed dog 225 fulcrumed on head 114 and adapted to engage wheel 224; a spring 226 for yieldingly holding dog 225 engaged with wheel 224; and a solenoid magnet 227 for shifting dog 225 to release wheel 224. Dog 225 and ratchet wheel 224 act to hold the hand-wheel 124 and the sleeve 112 and tool 105 until solenoid 227 is actuated to shift dog 225 to disengage it from wheel 224. The helix of magnet 227 is connected to a power circuit as illustrated in Fig. 38 which includes a relay-switch 228. When contact has been made between ball 150 in plate 147 (Fig. 30) on beam 140, current from a grounded low-voltage transformer 229 will pass through the magnet of

switch 228 and conductor 229a to plate 147 which is insulated from beam 140, ball 150, and the blank *a* to the frame of the machine which is connected to ground. The release of this brake does not occur until the ball 150 has contacted the blank *a*. A low-voltage signal lamp 230 (Fig. 38) is connected in parallel with the circuit for switch 228 to signal the operator that the contact-ball 150 on beam 140 has engaged the inner periphery of the blank *a* and that the brake on the tool 105 has been released by dog 225 in readiness for a milling operation.

A lamp 231 is included in a conductor 232 which is connected to the insulated stop-member 159 on beam 155 (Figs. 37 and 38) and to transformer 229. When stem 185 contacts insulated stop-member 159 which is carried by beam 155, which occurs when the spot has been milled to the predetermined depth, the circuit for lamp 231 will be closed to indicate the completion of the cut to the operator.

A suitable pedal controlled valve 260 is adapted to control the delivery of compressed or other fluid from a supply pipe 262 to one end of cylinder 80 for engaging brake 82, to lock the blank *a* against rotation and simultaneously to one end of cylinder 176 for operating wedge-bar 174 to lock beams 155 and 140. Valve 260 in its normal position supplies air to one end of cylinder 80 and exhausts air from other end for releasing brake 82 and the blank *a* and supplies air to one end of cylinder 176 and exhausts air from its other end, for retracting bar 174 to release beams 140, 155 for pivotal movement. When the valve-pedal is depressed, the air flow to and from cylinder 80 will be reversed to apply brake 82 to the blank *a* and reversed to and from cylinder 176 for shifting the wedge-bar 174 and releasing the beams 140, 155. A switch 271 for controlling motor 128 is mounted on arm 210 (Fig. 10).

A modification of the means for the angular adjustment of the milling tool 105 and its supports is illustrated in Figs. 39 to 41. This includes a cylinder 240 which has its rear end pivotally connected at 241 to a bed-supported bracket 242 and is provided with a piston, the stem 243 of which is pivotally connected at 244 to arm 210 which is fixed on post 115. Fluid, such as air under pressure, is alternately delivered into and exhausted from the ends of the cylinder by pipes 246 and 247, for operating the piston in opposite directions. A stop or abutment 249 is fixed to the underside of bracket 116 for engagement with variable stop means for arresting the bracket 116 in different angular positions. This stop-means comprises a disk 250 provided with stepped stop-faces 251 of different radii, trunnions journaled in a bracket 252, which is fixed to stationary bracket 119, and a handle 253 for rocking the disk. A spring detent 254 is pressed into notches in one side of disk 250, for yieldingly spotting the faces 251 in position for engagement by abutment 249. In this construction the pressure of fluid in cylinder 240 urges the bracket 116 so the abutment 249 and the disk will firmly hold the bracket in predetermined angular positions. A stop-pin 256 limits the rotative movement of disk 250.

The operation of the machine is as follows: the blank *a* to be spot-milled is partially fabricated by upsetting one end portion thereof to form a shank *a'*, shaping the tapered portion *a*³ and cam-turning the remaining cylindrical portion to provide the variations in the wall-thickness desired in the different portions of the lathe, such as

greater thickness at *a*⁵ for the leading and trailing edges and lesser wall-thickness between the said edges (Fig. 27b). The blank is punched marked as at 100 to rotatively spot the line along the leading edge line extending longitudinally of the blank. The calibrated roll 85 is rotated to position the line of calibrations corresponding to the line on the blank indicated by the punch mark 100 at the sight opening 103, and locked by turning screw 96 to cause members 95 to clamp roll 85 against rotation. The blank is then placed on rollers 76, 77 with its shank around the chuck member 71. The punch mark 100 is spotted in alignment with the pointer 101 which is pivotally supported so it can be swung to engage the blank. After the blank has been thus rotatively positioned on chuck member 71 hand-wheel 74 is rotated to expand jaws 70 into gripping engagement with the blank. Next the screw 96 will be turned to spread clamping members 95 and release the roll 85 so that the said roll and the blank will be conjointly rotatable through gears 92, 93. The calibrations on roll 85 will then be correctly co-related with the blank for milling the spots in the blank corresponding to the calibrations on roll 85. While the blank is being secured on carriage 57, the latter will be positioned at the left hand side of bed 50 so that the large end of the blank will be to the left of beam 140 and the latter will not extend into the blank. The carriage 57 will next be shifted to the right so the blank will extend around the contact-ball 150 on beam 140. The carriage with the blank thereon will be shifted by the operator longitudinally of the bed 50 to one of the predetermined longitudinal stations for spot milling at that station. The carriage 57 will be there locked against longitudinal movement by the dropping of dog 104 into one of the notches 67 in rod 60 of the carriage 57. At each longitudinal station the blank may be rotated on the carriage correspondingly to the calibrations of a circumferential series of roll 85 for spot milling corresponding series on the blank. The carriage 57 is successively moved from one longitudinal station to the next and the blank thereon is rotated on the carriage 57 at each longitudinal station, for milling each of the points desired. The ball 150 is supported by beam 140 in substantial axial alignment with the tool 105. The milling tool is operated as herein-after described for singly cutting the spots at the several longitudinal stations.

The operator will rotatively set wheel 196 to adjust the stop-plunger 185 so that the lowering movement of the milling tool 105 will be arrested by the stop-member 159 on the locked beam 155 when the milling tool has cut away the metal in the wall of the blade to leave the predetermined wall-thickness desired at each spot. This depth will be indicated by the pointer 198 on the calibrations 197 on wheel 196 and the grooves 202 on stem 193.

Assuming the blank *a* to have been secured on carriage 57 and positioned as before described for milling a spot, the counterweights 151 will press the contact-ball 150 on beam 140 into contact with the inner periphery of the shank of the blade and the stop-member 159 on beam 155 will be correspondingly positioned. The operator will then depress the pedal of valve 260 to supply compressed fluid to cylinder 80 to operate brake shoe 82 against the outer periphery of the shank of the blank and lock the blank and the calibrating roll against rotation on the carriage 57 and to simultaneously supply compressed fluid to cylin-

11

order 176 to operate wedge-bar 114 and cause stop 164 on beam 155 to be locked against vertical movement. Beam 155, being fixedly secured to swing with beam 140, causes the contact-ball 150 on beam 140 to be locked in its engaged position with the inner periphery of the blank of the blade at the spot to be milled. A circuit will then be closed from transformer 229, plate 147, ball 150 and the blank a to the grounded frame work of the machine. This lamp 230 will signal the operator that the contact-ball 150 is engaged with the blank.

Simultaneously, the relay-switch 228 will be energized and close a circuit through solenoid 227 which is connected to the power line. Solenoid 227 will release the brake-dog 225 from ratchet wheel 224 so that the drilling tool will be released for lowering movement. If the blank and contact 150 are not engaged, lamp 230 and relay-switch 228 will not be operated, thus indicating to the operator that the contact-ball 150 is not engaged with the blank.

Next the operator will rotate hand-wheel 124 which will lower sleeve 112 and the milling tool 105 carried thereby toward the blank a . During this lowering movement of the tool, it will be driven by motor 128 and the housing 111 will be guided in the bracket 116 and the sleeve 112 will be guided in the head 114. The lowering movement of the tool will be retarded by the engagement of dog 225 with ratchet wheel 224 until the dog is released by magnet 221. When, during the lowering movement of the tool 105, the stop-plunger 185 strikes stop-member 159 on beam 155 which is locked against vertical movement, the tool will be arrested against further downward movement to positively limit the depth of the milling cut correspondingly to the predetermined setting of the wheel 196. When plunger 185 engages stop-member 159 on beam 155 a circuit will be established from transformer 229 through lamp 231, contact 159 which is insulated from beam 155, and stop-plunger 185 to the supporting structure which is connected to ground, to indicate to the operator that the spot-milling operation to the predetermined depth has been completed. The operator will then release hand-wheel 124 and permit springs 127 to lift the tool 105 away from the blank. The operator will then release the pedal of valve 260 to reverse the air pressure in cylinders 180 to release brake-shoe 82 so the blank will be rotatable on carriage 57 and to reverse the air pressure in cylinder 176 to release the beams 140, 155. The operator can then shift the blank longitudinally or rotatively to present the next predetermined spot on the blank to the tool 105 and will set the wheel 196 for the depth of the cut desired at that spot.

When the tapered or longitudinally curved portion a^3 of the blank is to be spot-milled, the operator will turn handle or screw clamp 209 to release arm 210 from bracket 213 and rotate hand-wheel 220 which will, through shaft 219, gears 221 and screw shaft 216 operate runner 217 and shift arm 218 to tilt the tool-head 114 on pin 118 until the axis of the tool is substantially perpendicular to the surface of the blank at each spot to be milled. The handle 209 is then tightened to lock the said head in its adjusted position and the spot-milling operations on portion a^3 of the blank are carried on in the same manner as before described. The inclination of the tool will be indicated on the calibration scale 214 on the stationary member 212.

When the modified form of shifting mecha-

12

nism for the tool-head illustrated in Figs. 39-41 is used, handle 209 is rotated to set the stop surface 251 on disk 250, according to the longitudinal inclination of the tool-head desired. Compressed air is delivered into cylinder 249 which will exert pressure on the bracket 116 to force abutment 249 into engagement with said stop surface.

In practice, a chart is usually provided and maintained in a location visible to the operator with the specifications thereon of the wall-thickness desired at each of the spots to be milled for the convenience of the operator in setting the calibrated wheel 196 to correspondingly control the depth of each cut, and this chart may also contain the angular settings for the tool-head for its correct inclinations when milling spots in the portion a^3 of the blade.

After the blank has been spot-milled at the predetermined points longitudinally and circumferentially of the outer periphery of the blank, the latter is subjected to the action of an abrading or polishing belt and the metal is removed from the periphery to the precise depth of the milled spots or until the bottom surfaces of the milled spots blend smoothly into the surrounding surface of the blank. As a result, the wall-thickness of the depth desired in all portions of the blade may be achieved with great precision.

The invention exemplifies a machine for spot-milling propeller-tubular-blade blanks by which the blank may be milled with precision to leave the desired wall-thickness in accordance with predetermined calibrations. The machine meets the requirements of great precision required in the fabrication of hollow steel propeller blades. The machine can be expeditiously operated and includes means for locking the inner element for contacting the blank during the milling operation and also means for rotatively locking the blank during the milling operation. The machine also provides means for angularly adjusting the tool for operation on an axis which is perpendicular to the tapered or longitudinally curved surface on the blank, and means for indicating to the operator when foreign matter is present between the inner contact for the blank, and the means for indicating the completion of the milling operation when the tool has reached the desired depth in the wall of the blank. The use of the machine results in substantial savings in the cost of fabrication in the blade by guarding against production of blades with walls which are too thin to meet the requirements of the work of the blade.

The invention is not to be understood as limited to the details set forth since these may be modified within the scope of the appended claims without departing from the spirit and scope of the invention.

Having thus described the invention, what I claim as new and desire to secure by Letters Patent is:

1. A machine for spot-milling tubular blanks for use in the fabrication of propeller blades comprising: a longitudinally movable carriage for the blank; means for rotatably supporting the blank on the carriage; a power driven tool for cutting spots in the outer face of, and mounted to move to and from the blank; and means including a member for engaging the inner face of the blank, for limiting the depth of the cut to leave predetermined thickness in the wall of the blank.

2. A machine for spot-milling tubular blanks for use in the fabrication of propeller blades comprising: a longitudinally movable carriage for the blank; a power driven tool for cutting spots in the outer face of and mounted to move to and from the blank; means for limiting the depth of the cut to leave predetermined wall thickness in the blank, including a stop-member for engaging the inner face of the blank, and co-acting stop-members one of which is movable with the tool during its cutting stroke, and the other of which is movable with the member engaging said inner face.

3. A machine for spot-milling tubular blanks for use in the fabrication of propeller blades comprising: a longitudinally movable carriage for the blank; means adapted to enter the blank and engage its inner face; a power driven tool for cutting spots in the outer face of and mounted to move to and from the blank; and means for limiting the depth of the cut to leave predetermined wall thickness in the blank, including a stop-member carried by said first-named means for engaging the inner face of the blank; co-acting stop-members, one of which is movable with the tool and the other movable with the member for engaging said inner face; and means for adjusting the member movable with the tool relatively thereof.

4. A machine for spot-milling tubular blanks for use in the fabrication of propeller blades comprising: a longitudinally movable carriage for the blank; a power driven tool mounted in its outer face; and means for limiting the depth of the cut by the tool to leave the predetermined wall-thickness in the blank including a pair of conjointly and pivotally movable beams, one adapted to extend into the blank and provided with means for engaging its inner face, the other extending outside of the blank and provided with a stop-member and a stop-member co-acting with the stop-member outside of the blank, the last-named stop-member being movable with the tool to and from the blank.

5. A machine for spot-milling tubular blanks for use in the fabrication of propeller blades comprising: a longitudinally movable carriage for the blank; a power driven tool mounted for movement to and from the blank for cutting spots in its outer face; means for limiting the depth of the cut by the tool to leave the predetermined wall-thickness in the blank including a pair of conjointly and pivotally movable beams, one adapted to extend into the blank and provided with means for engaging its inner face, and the other extending outside of the blank and provided with a stop-member, and co-acting with the stop-member outside of the blank and movable with the tool to and from the blank; and means for adjusting the coacting stop-member for varying the depth of the cuts by the tool.

6. A machine for spot-milling tubular blanks for use in the fabrication of propeller blades comprising: a longitudinally movable carriage for the blank; a power driven tool mounted for movement to and from the blank for cutting spots in its outer face; means for limiting the depth of the cut by the tool to leave the predetermined wall-thickness in the blank including a pair of conjointly and pivotally movable counterweighted beams, one adapted to extend into the blank and provided with means for engaging its inner face, and the other extending outside of the blank and provided with a stop-member, and a coacting stop-member outside of the blank and movable

with the tool to and from the blank; and means for adjusting the coacting stop-member for varying the depth of the cuts by the tool.

7. A machine for spot-milling tubular blanks for use in the fabrication of propeller blades comprising: a longitudinally movable carriage for the blank; a power driven tool mounted for movement to and from the blank for cutting spots in its outer face; means for limiting the depth of the cut by the tool to leave predetermined wall-thickness in the blank including a pair of conjointly and pivotally movable beams, one adapted to extend into the blank and provided with the means for engaging its inner face, and the other extending outside of the blank and provided with a stop-member, and a stop-member co-acting with the stop-member outside of the blank and movable with the tool to and from the blank; a signaling device; and means controlled by the engagement of the stop-member on the inner beam for controlling the operation of said signal device.

8. A machine for spot-milling tubular blanks for use in the fabrication of propeller blades comprising: a longitudinally movable carriage for the blank; a power driven tool mounted for movement to and from the blank for cutting spots in its outer face; means for variably limiting the depth of the cut by the tool to leave predetermined wall-thickness in the blank including a pair of conjointly and pivotally movable beams, one adapted to extend into the blank and provided with means for engaging its inner face, and the other extending outside of the blank and provided with a stop-member, and a stop-member co-acting with the stop-member outside of the blank and movable with the tool to and from the blank; a signaling device; and means controlled by the engagement of the stop-member movable with the tool and the stop-member on the outside beam, for controlling the operation of said signal device.

9. A machine for spot-milling tubular blanks for use in the fabrication of propeller blades comprising: a longitudinally movable carriage for the blank; means for rotatably supporting the blank on the carriage; an element rotatably mounted on the carriage calibrated for indicating predetermined points for the spots to be cut on the blank; means for conjointly rotating said element and the blank; a power driven tool for cutting spots at said predetermined points mounted for movement to and from the blank; and means for limiting the depths of the cuts to leave the desired wall-thickness in the blank at said points.

10. A machine for spot-milling tubular blanks for use in the fabrication of propeller blades comprising: a longitudinally movable carriage for the blank; means for rotatably supporting the blank on the carriage; an element rotatably mounted on the carriage calibrated for indicating predetermined points for the spots to be cut on the blank; means for conjointly rotating said element and the blank; means for locking the blank and element against rotation; a power driven tool for cutting spots at said predetermined points mounted for movement to and from the blank; and means for limiting the depths of the cuts to leave the desired wall-thickness in the blank at said points.

11. A machine for spot-milling tubular blanks for use in the fabrication of propeller blades comprising: a longitudinally movable carriage for the blank; means for rotatably supporting the blank on the carriage; an element rotatably

mounted on the carriage calibrated for indicating the longitudinal and rotative location of predetermined points to be cut on the blank; means for conjointly rotating said element and the blank; a power driven tool for cutting spots at said predetermined points mounted for movement to and from the blank; and means for limiting the depths of the cuts to leave the desired wall-thickness in the blank at said points.

12. A machine for spot-milling tubular blanks for use in the fabrication of propeller blades comprising: a longitudinally movable carriage for the blank; means for rotatably supporting the blank on the carriage; an element rotatably mounted on the carriage calibrated for indicating the longitudinal and rotative location of predetermined points to be cut on the blank; means for conjointly rotating said element and the blank; a power driven tool for cutting spots at said predetermined points movable to and from the blank; means for releasing the blank for rotation on the carriage; and means for variably limiting the depths of the cuts to leave the desired wall-thickness in the blank at said points.

13. A machine for spot-milling tubular blanks for use in the fabrication of propeller blades comprising: a longitudinally movable carriage for the blank; means for rotatably supporting the blank on the carriage; an element rotatably mounted on the carriage calibrated for indicating the longitudinal and rotative location of predetermined points to be cut on the blank; means for conjointly rotating said element and the blank; a power driven tool for cutting spots at said predetermined points movable to and from the blank; means for releasing the blank for rotation on the carriage; and releasable means for locking the element against rotation; and means for variably limiting the depths of the cuts to leave the desired wall-thickness in the blank at said points.

14. A machine for spot-milling tubular blanks for use in the fabrication of propeller blades comprising: a longitudinally movable carriage for the blank; a power driven tool for cutting spots in the outer face of the blank and movable to and from the blank; means for supporting the tool at different inclinations for cutting spots on different axes along longitudinally varying portions of the outer face of the blank; and means for limiting the depth of the cut by the tool to leave predetermined wall-thickness in the wall of the blank, including a movable member adapted to extend into and engageable with the inner face of the blank and a member movable to different inclinations with the tool.

15. A machine for spot-milling tubular blanks for use in the fabrication of propeller blades comprising: a longitudinally movable carriage for the blank; a power driven tool mounted for movement to and from the blank for cutting spots in its outer face; means for limiting the depth of the cut of the tool to leave the desired wall-thickness in the blank, including a member adapted to extend into, and engage the inner face of, the blank; brake means for holding the tool against movement toward the blank; and means controlled by the contact of the member of said member with the inner face of the blank, for releasing the brake.

16. A machine for spot-milling blanks for use in the fabrication of propeller blanks comprising: a longitudinally movable carriage for the blank;

a power driven tool mounted for movement to and from the blank for cutting spots in its outer face; means for limiting the depth of the cut of the tool to leave the desired wall-thickness in the blank, including a movable member adapted to extend into and engage the inner face of the blank and a member outside of the blank and movable with the inner member; and means acting on the outer member for locking said members against movement during the cut.

17. A machine for spot-milling blanks for use in the fabrication of propeller blanks comprising: a longitudinally movable carriage for the blank; a power driven tool mounted for movement to and from the blank for cutting spots in its outer face; means for limiting the depth of the cut of the tool to leave the desired wall-thickness in the blank, including a movable member adapted to extend into and engage the inner face of the blank and a member outside of the blank and movable with the inner member and fluid pressure operable; and means acting on the outer member for locking said members against movement during the cut.

18. A machine for spot-milling tubular blanks for use in the fabrication of propeller blanks comprising: a longitudinally movable carriage for the blank; a power driven tool mounted for movement to and from the blank for cutting spots in its outer face; means for limiting the depth of the cut of the tool to leave the desired wall-thickness in the blank, including a pair of conjointly movable members, one adapted to extend into and engage the inner face, and the other outside of the blank, and a co-acting member movable with the tool; and means controlled by the last two members for signaling the completion of the cut.

19. A machine for spot-milling tubular blanks for use in the fabrication of propeller blades comprising: a longitudinally movable carriage for the blank; means for supporting the blank on the carriage for rotation on its longitudinal axis; a power driven tool for cutting spots in the outer face of and mounted to move to and from the blank; means, including a member for engaging the inner face of the blank, a member outside of the blank, and a co-acting member movable with tool, for limiting the depth of the cut to leave predetermined thickness in the wall of the blank; a brake for arresting the cutting stroke of the tool, and means controlled by the engagement of the inner member with the blank for controlling the brake.
